UNITED STATES PATENT OFFICE.

JOHN B. BENTON, OF ELIZABETH, NEW JERSEY, ASSIGNOR TO THE STERLING SUPPLY AND MANUFACTURING COMPANY, OF NEW YORK.

DESIGN FOR A FACE-PLATE FOR FARE-REGISTERS.

SPECIFICATION forming part of Design No. 24,755, dated October 15, 1895.

Application filed October 16, 1894. Serial No. 528,103. Term of patent 14 years.

To all whom it may concern:

Be it known that I, JOHN B. BENTON, a citizen of the United States, residing at Elizabeth, in the county of Union and State of New Jersey, have invented and produced a new and original Design for the Face-Plate of a Fare-Register, of which the following is a specification, reference being had to the accompanying drawings, which form a part hereof.

Figure 1 is a front or face view of a face-plate, showing my design; and Fig. 2 is a section on the line $x-x$ in Fig. 1.

The leading feature of my design consists in a circular face-plate having at the center an opening surrounded by a raised bead or molding concentric with the peripheral edge of the plate and two rectangular openings located, respectively, above and below the central opening and bordered by raised beads or moldings in representation of rectangular frames.

A designates the face-plate of circular form, having at the center an opening B, surrounded by a raised bead or molding b, concentric with

the peripheral edge of the plate. Vertically above and below the opening B are two openings C D, of rectangular form and surrounded at a short distance from their edges by raised beads or moldings c d, in representation of rectangular frames, the plain surfaces c' d' within the respective moldings forming representations of mats for the frames.

What I claim is—

The design for the face plate of a fare-register herein shown and described, the same comprising a circular plate A having a central opening B, a raised bead or molding encircling said opening, rectangular openings C, D, located respectively above and below the central opening and surrounded by raised beads or moldings in representation of rectangular frames, as set forth.

In witness whereof I have hereunto set my hand this 26th day of September, 1894.

JOHN B. BENTON.
